UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

DESIGN FOR AN AUTOMOBILE-HORN.

42,971.

Specification for Design.

Patented Sept. 3, 1912.

Application filed March 2, 1912. Serial No. 681,278. Term of patent 7 years.

To all whom it may concern:

Be it known that I, RAY H. MANSON, a citizen of the United States, residing at Elyria, in the county of Lorain and State of Ohio, have invented a new, original, and ornamental Design for Automobile-Horns, of which the following is a specification, reference being had to the accompanying drawing, forming a part thereof.

The figures show my improved design.

Figure 1 is a side view of a horn illustrating my invention. Fig. 2 is a perspective view of the horn shown in Fig. 1.

I claim:

The ornamental design for an automobile horn as shown.

RAY H. MANSON.

Witnesses:

A. D. T. LIBBY,
F. O. RICHEY.
